(57) **CLAIM**

The ornamental design for a projecting front portion of a vending machine bezel, as shown and described.

DESCRIPTION

FIG. 1 is a perspective view of the projecting front portion of a vending machine bezel;

FIG. 2 is a bottom view thereof;

FIG. 3 is a front view thereof;

FIG. 4 is a left view thereof;

FIG. 5 is a right view thereof; and,

FIG. 6 top view thereof.

The vending machine bezel is intended for attachment to a vending machine. The broken line representations of the rear attachment portions of the vending machine bezel are for purposes of illustration only and form no part of the claimed design. The rear appearance of the vending machine bezel also forms no part of the claimed design.
